Frank Keiper Attorney

UNITED STATES PATENT OFFICE

JOHN SCHLEINZER, OF ROCHESTER, NEW YORK

TOOL FOR REMOVING CAPS FROM JARS

Application filed April 6, 1928. Serial No. 267,971.

The object of this invention is to provide a new and improved wrench or handle for removing the caps from glass jars, etc.

Another object of the invention is to make 5 the wrench of sheet metal and make it so that it will fit two different sizes of caps.

Another object is to make the wrench with a central disc and provide gripping fingers or lugs on the rim of the disc that extend 10 both up and down from the central disc which lugs interchangeably serve as gripping fingers to grip the cap, or as a handle by which the wrench may be more conveniently turned.

These and other objects of the invention 15 will be fully illustrated in the drawings, described in the specification and pointed out in the claims at the end thereof.

In the drawings:

Figure 1 is a perspective view of the glass 20 jar with the wrench suspended above it ready to engage with the cap on the jar.

Figure 2 is a side elevation of the jar with the wrench in position on the cap.

Figure 3 is a side elevation of the wrench 25 in which one set of fingers are made corrugated so as to form a mutilated thread by which they may be screwed into engagement with the cap. The other set of fingers are made eccentric to the rim so that on one side 30 they will present an edge to the cap which is better adapted to engage the cap.

Figure 4 is a detail perspective view of a modified form of one of the gripping fingers of the wrench.

Figure 5 is another detail perspective view 35 of a modified form of one of the gripping fingers of the wrench.

In the drawings like reference numerals indicate like parts.

In the drawings reference numeral 1 indicates a glass jar having a metal cap 2 thereon which jar and cap is similar to what is ordinarily used in dispensing mustard, jelly, peanut butter, etc. 3 indicates the wrench 40 having a disc in the center on the rim of which are formed three radial extensions 4, 4, 4 on the outer end of which are formed upturned fingers 5, 5. Also formed on the edge of the disc of the wrench are three downwardly extending fingers 6, 6, 6. The fin-

gers 6, 6, 6 are spaced apart on a smaller circle having a shorter diameter and the fingers 5, 5, 5 are spaced apart on a larger circle having a longer diameter. The wrench is formed of a single sheet of metal in which 55 the six fingers are stamped out integral therewith, the fingers 5, 5, 5 being turned up and the fingers 6, 6, 6 being turned down. The fingers 6, 6, 6 are used to engage a cap of small diameter and the fingers 5, 5, 5 are used 60 to engage a cap of larger diameter. The wrench is used by simply forcing the fingers down over the sides of the cap until the disk of the wrench rests on top of the cap. The operator will then press the lower fingers in 65 against the cap and will turn the wrench, using the upwardly extending fingers as handles by which to force the turning of the wrench, and all of this can be done with one hand.

Ordinarily the downwardly extending fingers will engage the cap firmly enough to hold it to force the turning of the cap without pressing the fingers of the wrench together 75 with the fingers of the hand. This is due to the fact that the caps of jars are ordinarily provided with a beaded rim which extends outwardly from the glass jar and which will cause the gripping fingers to spring out thus causing the wrench to more securely engage 80 the cap, and hold it in engagement therewith with yielding pressure. By turning the cap and wrench on the jar, the cap can easily and quickly be removed from the jar.

In Figure 3 I have shown one set of the gripping fingers 8, 8, 8 corrugated, the corrugations forming a mutilated thread which engages the beaded edge of the cap and serves to draw the wrench down firmly on the cap 90 and hold the wrench firmly in engagement with the cap so that the cap may be positively turned thereby.

I have also shown the upwardly extending fingers 9, 9, 9 formed slightly eccentric to a tangent to the rim at the point where the fingers are placed. With the fingers formed in this way the forward edge tends to cut into the cap or the beaded edge thereof thus making a more positive engagement therewith by 100

which to force the turning of the cap on the jar and secure the removal thereof.

In Figure 4 I have illustrated another modified form of the gripping fingers which is made by concaving the outside of the fingers as illustrated so that a curved convex surface is presented to the cap when the fingers come in contact therewith.

The modification illustrated in Figure 5
10 shows the finger concaved on the inside so that when the fingers are brought in contact with the cap the sharp edges on each side of the fingers are brought in contact with the cap.

15 I claim:

1. A wrench for removing the caps of jars comprising a disc, fingers formed on the periphery of said disc and extending downward therefrom, said fingers being adapted to engage the rim of the cap to turn and lift the cap, said wrench having fingers extending up therefrom by which said wrench may be better grasped and turned and raised.

2. A wrench for removing the caps of jars
25 comprising a disc, fingers formed on the periphery of said disc and extending downward therefrom, said fingers being adapted to engage the rim of the cap to turn and lift the cap, said wrench having fingers extending up
30 therefrom by which said wrench may be better grasped and turned and raised, the fingers on each side of the disc being adapted to grasp a cap, the fingers on one side being adapted to grasp a cap of larger diameter and the fingers
35 on the other side being adapted to grasp a cap of small diameter.

3. A wrench for removing the caps of jars comprising a disc, fingers formed on the periphery of said disc and extending downward
40 therefrom, said fingers being adapted to engage the rim of the cap to turn and lift the cap, said wrench having fingers extending up therefrom by which said wrench may be better grasped and turned and raised, the fingers
45 on one side of the disc having corrugations therein forming a mutilated thread therein, the fingers on the other side of the disc being eccentrically placed so that one edge of each finger is better adapted to engage the rim of
50 the cap.

4. A wrench for removing the caps of jars comprising a disc, fingers depending from the periphery of said disc and adapted to yieldingly engage the sides of a cap when said disc is forced down on top of said cap, and fingers projecting upwardly from said disc to form a handle for said wrench.

In testimony whereof I affix my signature.

JOHN SCHLEINZER.
